(57) **CLAIM**

The ornamental design for a connector for modular racks, as shown and described.

DESCRIPTION

FIG. 1 is a perspective view of new design for a connector for modular racks as shown in the drawings;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view.

1 Claim, 4 Drawing Sheets
